UNITED STATES PATENT OFFICE.

JOHN STEPHENSON, OF NEW YORK, N. Y.

CAR-AXLE BOX.

SPECIFICATION forming part of Letters Patent No. 292,379, dated January 22, 1884.

Application filed April 21, 1883. (No model.)

To all whom it may concern:

Be it known that I, JOHN STEPHENSON, of the city, county, and State of New York, have invented certain Improvements in Car-Axle Boxes, of which the following is a specification.

My improvement consists of a shell for car-axle boxes especially adapted for use in connection with necked axles secured by key 10 check-plates, as fully described herinafter and as fully illustrated in the accompanying drawings, in which—

Figure 1 is a longitudinal section of an axle-box, showing its connection with the axle, 15 pedestal, car, and guard-arm, and illustrating my improvements. Fig. 2 is a sectional plan of the box.

My improved axle-box shell A will vary somewhat in form and dimensions, according 20 to circumstances. As shown in the drawings, it has vertical grooves α in the side walls for receiving a forked check-plate, B, the axle being prolonged so as to form a neck or channel, a , near the outer end, to receive the said plate, whereby the longitudinal movement of 25 the box and axle independently of each other is prevented.

In order to accommodate the increased length of axle resulting from the construction 30 above described, the front wall, t' , is curved outward beyond the line which it would otherwise occupy, as shown in Fig. 2, and the cap C is hung at the top by an open-jointed hinge consisting of a curved lip, p , fitting a 35 slot in the cap, so as to be easily removable, and is sprung and held by the bolt E, so as to fit closely to the curved edges of the sides, covering the opening in the box and projecting at an angle over and above the axle. The 40 bulged form of the front of the box not only affords room for the neck of the axle, but also presents a rounded surface, so that the box will glance off from objects that it may strike, thus preventing injuries that would otherwise 45 result from contact with such objects. The limbs of the check-plate extend into the grooves α and downward into the oil-well, so that the fluttering of the plate in its grooves squirts the oil upward against the inclined face 50 of the box-cover, by which it is deflected into a basin, y , at the top of a bearing, D, from whence it runs through openings w onto the

journal. Lips c cover, one the front edge of the opening in the box, and the other the opening u , through which the lip or hook p of the 55 cover passes, thereby preventing the escape of oil at these points. At each side of the box, near the center, is a vertical projection or swelling, g , for contact with the journal-bearing, leaving room at the ends for the bearing 60 to swing to either side as the axle changes its angle to the box.

I claim—

1. A car-axle-box shell having its front wall bulged outward from each side, and with a 65 front opening provided with a cap curved or bent inward at each side, substantially as set forth.

2. A car-axle-box shell with grooves in its side walls to receive the key check-plate of 70 the necked axle, and with the box-cap to overshoot the check-plate and bearing-block at an angle relative to the said plate and block, substantially as set forth.

3. An axle-box shell having a curved front 75 end, and provided with a cover plate or cap hinged at the upper end to the box and curved so as to bend its bearing under the action of the clamping-bolt, substantially as described.

4. An axle-box provided with grooves for 80 a key check-plate adapted to a grooved axle, adapted to receive a bearing having a basin at the upper side, and a curved cap arranged to deflect the oil into the basin, substantially as set forth.

5. A car-axle box provided with a cap, the upper part of which extends over the check-plate, and the lower part of the cap passes down outside of front wall, the cap having a ledge or lip at its inner side covering the upper edge of the front wall, as and for the purposes described.

6. The combination of the box and cap extended at an angle over the end of the axle, and provided with a curved lip, p , and flange e , 95 substantially as set forth.

In testimony whereof I have signed my name to this specification in the presence of two subscribing witnesses.

JOHN STEPHENSON.
